UNITED STATES PATENT OFFICE.

JOHN H. SATTLER, OF SAN FRANCISCO, CALIFORNIA.

COMBINED COAL AND GAS STOVE.

1,352,539.

Specification of Letters Patent. Patented Sept. 14, 1920.

Application filed August 7, 1919. Serial No. 315,847.

To all whom it may concern:

Be it known that I, JOHN H. SATTLER, a citizen of the United States, and a resident of the city and county of San Francisco and 5 State of California, have invented a certain new and useful Combined Coal and Gas Stove, of which the following is a specification.

The invention relates to stoves which may 10 be heated with gas or with coal or wood.

An object of the invention is to provide, in a stove of the class described, an oven which is efficiently and quickly heated either by the gas or by the coal fire.

15 Another object of the invention is to provide a stove in which the oven is quickly and uniformly heated by the gas fire.

A further object of the invention is to 20 provide a stove of the class described, which is easily and quickly converted from a coal burner to a gas burner and vice versa.

The invention possesses other advantageous features, some of which, with the foregoing, will be set forth at length in the following description, where I shall outline in full, that form of the invention which I have selected for illustration in the drawings accompanying and forming part of the present specification. In said drawings, I have 25 shown one specific embodiment of my invention, but it is to be understood that I do not limit myself to such form, since the invention, as expressed in the claims, may be embodied in a plurality of forms.

30 Referring to said drawings:

Figure 1 is a vertical longitudinal section through the stove of my invention.

Fig. 2 is a section taken on the line 2—2, Fig. 1, one of the gas burners being omitted 40 to disclose the air damper.

Fig. 3 is a section taken on the line 3—3, Fig. 1.

Fig. 4 is a section taken on the line 4—4, Fig. 1.

45 The present invention relates particularly to the construction and arrangement of the oven, flues and gas burners within the stove, so that the oven is properly heated when either the gas or the coal fire is being used.

50 The heat for baking or roasting is applied differently when coal is burned than when gas is burned, and the stove is constructed to accommodate this difference. When coal is used as fuel, the food in the oven is heated 55 by radiation, since the products of combustion do not come into contact with the food.

When gas is employed, the food is heated by direct contact with the products of combustion, which enter the oven. In accordance with my invention, I arrange gas burners in 60 large combustion chambers disposed at opposite sides of the oven and freely open to the atmosphere, so that the gases of combustion are conducted directly into the oven. The burners are arranged at the side of the 65 oven, preventing overheating of the oven bottom, a condition which causes food in the oven to burn on the bottom.

The stove of my invention is provided with a suitable fire box 2, provided with a grate 70 3, for the burning of coal, wood or other fuel. From the fire box, the products of combustion of the coal fire pass into the chamber or flue 4, formed between the top 5 of the stove and the top oven plate 6. From this chamber, the gases may pass directly into the upper part of the forward rear flue 7 which is connected directly to the chimney, this passage of the gases being controlled by the damper 8, which when closed causes the 80 gases to pass downward through the back rear flue 9, into the back bottom flue 12, formed between the bottom 13 of the stove and the bottom oven plate 14. The gases pass forward in the back bottom flue 12, pass 85 around the end of the partition wall 15, which separates the forward flues from the back flues, and pass rearwardly in the forward bottom flue 16, into the forward rear flue 7, whence they pass into the chimney. 90 The gases of combustion, therefore, pass across the top, across the rear and across the bottom of the oven. The rear flues are formed between the rear oven plate 17 and the rear wall 18. The oven is closed at the 95 front, by the front oven plate 21, and at the back by the back oven plate 22, both of which plates extend from the top oven plate 6 to the bottom 13 of the stove. The combined width of the bottom flues 12 and 16 is 100 less than the width of the oven, so that the side plates 23—24 of the flues are spaced from the front and back oven plates 21 and 22, forming passages or chambers 25—26 on opposite sides of the bottom flues. 105

Disposed within the oven at the sides thereof and spaced from the front and back plates 21—22, are apertured inner plates 27—28, which are aligned with or form extensions of the side plates 23—24, so that the passages 110 25—26 extend upwardly to the top of the oven. The plates 27—28 are each provided

with an aperture 31 disposed at the bottom of the oven, an aperture 32 disposed midway of the height of the oven and an aperture 33 disposed at the top of the oven.

5. Arranged within the passages 25 and 26 and disposed opposite the bottom apertures 31, are gas burners 34—35 which are connected across the rear of the oven.

10. The gas burners are disposed to direct the gas flames against the plates 27—28 immediately above the bottom apertures. The gases of combustion of the gas fire enter the oven through all of the apertures in the plates 27—28 causing an equal distribution of heat throughout the oven. The air for the combustion of the gas enters the passages 25 and 26 through apertures 36 in the bottom 13. These apertures are controlled by dampers 37—38, having apertures and cross bars, 20 so that longitudinal movement of the dampers opens or closes the apertures 36. The dampers are connected together at the rear by the cross lever 39 which is pivoted at its center to the stove bottom 13, so that the dampers move together. When the coal fire is used, the dampers 37—38 are closed, and when the gas fire is used the dampers are opened.

30. The gases of combustion of the gas fire discharge from the oven through a plurality of apertures 41 formed in the rear oven plate 17 adjacent the bottom of the oven and pass into the rear flues 7 and 9. By discharging these gases from the bottom of the oven, a 35 complete circulation of the gases through the oven, before their discharge, is insured.

I claim:

1. In a combined coal and gas stove, a front oven plate, a back oven plate and a bottom oven plate inclosing an oven, a flue for the gases of combustion of the coal fire arranged below the bottom oven plate, said flue and said bottom oven plate being of less width than the oven, whereby passages are formed 45 between the flue and the front and back oven plates, apertured plates in said oven spaced from the front and back oven plates and forming with said plates, continuations of said passages, gas burners in said passages, and means for controlling the flow of air into said passages.

2. In a combined coal and gas stove, a front oven plate, a back oven plate and a bottom oven plate inclosing an oven, a flue for the gases of combustion of the coal fire arranged below the bottom oven plate, said flue being coextensive with the bottom oven plate and the side walls of the flue being spaced from said front and back oven plates, 55 apertured plates in said oven spaced from said front and back oven plates and forming with said plates and with the side walls of the flue, passages extending upwardly on both sides of the oven, and gas burners in said 60 passages.

3. In a combined coal and gas stove, a front oven plate, a back oven plate and a bottom oven plate inclosing an oven, a flue for the gases of combustion of the coal fire arranged below the bottom oven plate, said flue being coextensive with the bottom oven plate and the side walls of the flue being spaced from said front and back oven plates, 70 apertured plates in said oven spaced from said front and back oven plates and forming with said plates and with the side walls of the flue, passages extending upwardly on both sides of the oven, and gas burners in said passages disposed adjacent the bottom oven plate.

4. In a combined coal and gas stove, a front oven plate, a back oven plate and a bottom oven plate inclosing an oven, a flue for the gases of combustion of the coal fire arranged below the bottom oven plate, said flue being coextensive with the bottom oven plate and the side walls of the flue being spaced from said front and back oven plates, 75 apertured plates in said oven spaced from said front and back oven plates and forming with said plates and with the side walls of the flue, passages extending upwardly on both sides of the oven, and gas burners in said 80 passages, and means at the bottom of the passages for controlling the admission of air thereto.

5. In a combined coal and gas stove, a front oven plate, a back oven plate and a bottom oven plate inclosing an oven, a flue for the gases of combustion of the coal fire arranged below the bottom oven plate, said flue being coextensive with the bottom oven plate and the side walls of the flue being spaced from said front and back oven plates, 90 apertured plates in said oven spaced from said front and back oven plates and forming with said plates and with the side walls of the flue, passages extending upwardly on both sides of the oven, gas burners in said 95 passages, and means at the bottom of the passages for controlling the admission of air thereto.

6. In a combined coal and gas stove, a front oven plate, a back oven plate and a bottom oven plate inclosing an oven, a flue for the gases of combustion of the coal fire arranged below the bottom oven plate, said flue being of less width than the oven and having side walls spaced from said front and back oven plates, inner plates in said 100 oven spaced from said front and back oven plates and forming with said plates and with the side walls of said flue, passages extending upwardly on both sides of the oven, said inner plates being provided with 105 apertures at the bottom thereof and with other apertures above the bottom, and gas burners arranged in said passages opposite the dampers together.

7. In a combined coal and gas stove, a front oven plate, a back oven plate and a bottom oven plate inclosing an oven, a flue for the gases of combustion of the coal fire arranged below the bottom oven plate, said flue being of less width than the oven and having side walls spaced from said front and back oven plates, inner plates in said 110 oven spaced from said front and back oven plates and forming with said plates and with the side walls of said flue, passages extending upwardly on both sides of the oven, said inner plates being provided with apertures at the bottom thereof and with other apertures above the bottom, and gas burners arranged in said passages opposite the bottom apertures.

8. In a combined coal and gas stove, a 115

front oven plate, a back oven plate and a bottom oven plate inclosing an oven, a flue for the gases of combustion of the coal fire arranged below the bottom oven plate, said flue being of less width than the oven and having side walls spaced from said front and back oven plates, inner plates in said oven spaced from said front and back oven plates and forming with said plates and with the side walls of said flue, passages extending upwardly on both sides of the oven, said inner plates being provided with apertures at the bottom thereof and with other apertures above the bottom, gas burners arranged in said passages opposite said bottom apertures, and dampers for controlling the admission of air to said passages, disposed below said burners.

8. In a combined coal and gas stove, a front oven plate, a back oven plate and a bottom oven plate inclosing an oven, a flue for the gases of combustion of the coal fire arranged below the bottom oven plate, said flue being of less width than the oven and having side walls spaced from said front and back oven plates, inner plates in said oven spaced from said front and back oven plates and forming with said plates and with the side walls of said flue, passages extending upwardly on both sides of the oven, said inner plates being provided with bottom, top and intermediate apertures, and gas burners arranged in said passages opposite said bottom apertures.

35 9. In a combined coal and gas stove, a front oven plate, a back oven plate and a bottom oven plate inclosing an oven, inner

apertured plates spaced from the front and back oven plates and forming therewith passages extending upwardly for the height 40 of the oven, and gas burners arranged in said passages adjacent the bottom, a coal gas flue formed between the lower ends of the inner plates and extending below the oven bottom, a rear oven plate having outlet apertures, and a flue behind the rear plate connecting with the bottom flue.

10. In a combined coal and gas stove, a front oven plate, a back oven plate, a bottom oven plate and a rear oven plate inclosing an oven, a flue for the gases of combustion of the coal fire disposed behind said rear oven plate, a flue for the said gases disposed below said bottom oven plate, said flue being of less width than the oven and 50 having side walls, spaced from said front and back oven plates, apertured plates in said oven spaced from said front and back oven plates, and forming therewith and with said side walls, passages extending upwardly 55 on opposite sides of the oven, gas burners in said passages, means for controlling the admission of air into said passages and discharge passages for the gases from the oven passing through the rear oven plate adjacent the bottom oven plate and connecting the oven with said rear flue.

In testimony whereof, I have hereunto set my hand at San Francisco, California, this 31st day of July, 1919.

JOHN H. SATTLER.

In presence of—

A. W. HEALEY,
C. S. EVANS.
